UNITED STATES PATENT OFFICE.

CYRUS M. CARNAHAN, OF ALLEGHENY, PENNSYLVANIA, ASSIGNOR TO NATIONAL ROLLED STEEL CAR COMPANY, OF PITTSBURG, PENNSYLVANIA, A CORPORATION OF NEW JERSEY.

METALLIC CAR.

SPECIFICATION forming part of Letters Patent No. 739,290, dated September 22, 1903.

Application filed April 1, 1902. Serial No. 100,989. (No model.)

To all whom it may concern:

Be it known that I, CYRUS M. CARNAHAN, a citizen of the United States, residing at Allegheny, in the county of Allegheny and State of Pennsylvania, have invented certain new and useful Improvements in Metallic Cars, of which the following is a specification, reference being had to the accompanying drawings, forming part of this specification, in

which—

Figure 1 is a side elevation of my improved dumping-car. Fig. 2 is a longitudinal vertical section on the line II II of Fig. 3. Fig. 3 is a plan view of the car. Fig. 4 is a cross-section, on an enlarged scale, taken on the line IV IV of Fig. 1. Fig. 5 is a similar view on the line V V of Fig. 1. Fig. 6 is a plan view, partially in section, of one end of the foundation-framework. Figs. 7 and 8 are detail views showing a jointed operating-lever in the closed and open positions, respectively. Fig. 9 is a partial cross-section showing the movable door. Fig. 10 is a partial longitudinal section, on a further enlarged scale, indicated by the line X X of Fig. 3. Fig. 11 is a similar view on the line XI XI of Fig. 3. Fig. 12 is a partial horizontal sectional view on the line XII XII of Fig. 4. Fig. 13 is a detail cross-sectional view similar to Fig. 4, illustrating a modified construction of bracing and supporting mechanism, the door-operating devices, &c., not being shown. Fig. 14 is a detail cross-sectional view similar to Fig. 5, but showing a modified construction of door. Figs. 15 and 16 are detail views illustrating the operating-lever and its outer locking-support. Fig. 17 is a partial longitudinal sectional detail view showing the front end of the foundation-framework.

My invention refers to an improved construction in metallic cars, more particularly hopper-bottom cars; and it consists in the features of construction as shown in the drawings and as hereinafter described.

The invention has in view the cheapening, strengthening, and simplifying in construction of what are known as "steel" cars, more particularly dumping-cars, by the use of standard rolled sections of structural steel—such as channels, &c.—with portions comprising

the elements of the framing structure consisting of plate-partitions, bracing and supporting members, a series of individual doors, and the means for supporting and operating them, as shown and described.

55

Referring to the drawings, 2 2 are the center sills, made of structural shape, as channels, midway of the main framework, running longitudinally for the full length of the car, assembled in close relation to each other 60 and with sufficient intervening space to receive draw-heads 3, with their accompanying draft-gear, at each end. On each side, on corresponding levels with the center sills, are the side sills 4 of suitable structural shape, as 65 channels or I-beams, with which center sills and side sills are incorporated the end sills 5, likewise of similar structural members, incorporated with the side and center sills by suitable angle-brackets riveted to each, so as to 70 properly secure the parts together in the manner customary in structural work. Across the ends of the foundation structure from side to side above and below and secured to the center and side sills are the reinforcing 75 end-sill members 6 6 of suitable form, as channels, which serve to bind these parts securely together, giving a finished appearance, while the upper one of such members provides an end platform for the car. At the 80 corners are located the post members 7 and 8, of channel or other structural form, secured to the side and end sills and providing means for attachment and support of the sides 9, of plate metal, and also of the ends 10 of the 85 car, which posts, sides, and ends may be of any height desired. The ends 10 may be for the full depth or may be extended down to the upper ends of downwardly and inwardly inclined floor-plates 11, secured to the framework and constituting the floor portions at each end of the car. If desired, such floor portions may be laid flat upon the foundation structure and conforming to the general floor-level of the car.

95

Midway of the car at each outer side, mounted upon and secured to the side sills, are vertical post members 12, while above the body-bolsters, similarly mounted, are similar post members 13 of structural form, as chan-

100

nels, all of such side posts, with posts 7, being connected with upper longitudinal reinforcing members 14, of channel or other suitable shape.

5 The upper member 14 constitutes the upper portion of the side framework, to which framework is secured on the inside the sides 9 of the car, preferably of plates.

10 Midway of the length of the car, running across underneath from side to side, are supporting-bolsters 15, secured to the under side of the framework in any suitable manner, which project outwardly at each side sufficiently far to engage the supporting truss- 15 rods 16, which bear under and support the bolster and middle portion of the car, intervening shoes 17, secured to the bolsters, being preferably employed to provide suitable bearings for the rods.

20 The rods 16 are deflected upwardly and are secured to the body-bolster posts 13 at each end by passing through the flanges thereof and secured by nuts or in any other suitable manner reinforced by a supporting angle- 25 bracket underneath, and as thus arranged the rod constitutes a tension-truss at each side, by which the strain of the middle portion of the car is largely supported from above the body-bolsters over the trucks.

30 Oppositely arranged to the truss-rods 16, on each side, are the compression members 18 of structural form, as channels, bearing at the middle against the upper ends of posts 12 and underneath the top member 14 and sloping 35 downwardly in opposite directions, bearing against the posts 13 at or above the point where the tension-rods 16 are connected. These members 16 and 18 thus provide a diamond-shaped truss of great strength, stiff- 40 ness, and supporting power, and when the side members of the car are thus arranged and connected together and with the side plates the resulting structure provides sides of great simplicity, few parts, and ample strength for 45 the purpose in view. The sides are further reinforced by inner posts 19, midway of the car and at each side of the middle position, with an intervening distance equaling the width of the dumping-doors, hereinafter referred to, which posts are secured on the inner sides of the side sills 4 and to the intermediate cross members, which extend across at suitable intervals in the length of the car 50 between the side and center sills and provide 55 supporting-bearings for the door. These members consist of plates 20, secured to the center and side sills, with sufficient intervening space for mounting the supporting devices for the doors, the tops of each pair 60 of plates being covered by the flanges 21 of T members, the web 22 of which extends downwardly between the plates, as shown. The space between the web and the plates on each side is filled by suitable filler-blocks 23, 65 the plates, filler, and web being connected at intervals by rivets or bolts 24.

At the point where the floor portions 11

terminate at their inner ends they are supported upon and aline with, crosswise of the car, similar single cross-plates 25, which may, however, if desired, be of other form, as channels.

70 On the inside of the side plates 9, connected to and further reinforcing them, are the vertical posts 19, which are likewise connected with the cross-plates 20, and it will be seen that by such arrangement of cross-plates the floor of the car is divided longitudinally between the cross-plate-dividing floor portion and the terminals of the permanent floor 80 portions 11 into a series of intermediate openings or spaces. In the construction shown these are four in number on each side, although such number may be varied, as desired and according to the objects in view. 85 Extending downwardly and outwardly on each side of the center sills from the normal level of the floor at a suitable angle are inclined plates 26, while from the opposite sides, similarly arranged with relation to the side 90 sills, are similar plates 27, slanting inwardly. Such plates 26 and 27 constitute hoppers and provide reduced intervening longitudinal rectangular openings, which are covered beneath and closed by the shifting doors. In the form 95 shown in the principal figures of the drawings these doors consist of plates 28 of dimensions adapted to cover the openings reinforced by lateral and intervening flanged members 29, through which passes a bar or 100 shaft 30, supported between the cross-plates 20 on suitable swinging links or arms 31, as shown, the filler-block being suitably recessed for clearance. On each side the cross-plates are provided with angle members 32, which 105 may be located at or slightly above the lower edge of the cross-plates at each side, against which flanges the doors are adapted to bear in their closed position. Each door is provided with an operating handle or lever 33, 110 pivotally connected with the door at 34 by a bolt or rivet mounted in any suitable supporting-bearing, the operating-lever having stops 35 adapted to engage against the inner and outer sides of a bearing stirrup or 115 guide in the closed or open position of the door, respectively, and to hold it in said position. If preferred, the operating-lever may be jointed, as shown in Figs. 7 and 8, the joint preferably being provided with shoulders or knuckles permitting it to open upwardly, but not downwardly, in which case the door may be forced back when closed, while the joint in the lever will permit it to drop down vertically at the side of the car out 120 of the way when open, as shown in Fig. 8.

125 In Fig. 9 I have shown a modified construction of the door, in which the inner inclined floor 26' extends outwardly at a flatter angle, terminating nearer the outside of the car, 130 while the outer inclined floor 27' is more abrupt, the results of which arrangement is that the space between such floor members is so disposed that the weight of the contents of

the car will bear more directly against the floor members than against the door.

The door 28' consists of a plate of suitable dimensions to cover the intervening opening and is provided with a terminal bar pivotally mounted at 37 in bearings secured to the inner sides of the cross-plates, the door being stiffened or reinforced by an angle or suitable bracing member 38 and adapted to be opened and closed by the locking-lever 33 in the manner already described.

In Figs. 14 and 15 a construction is shown in which the ends of the inclined floor-plate 26" and 27" are similarly disposed, but in which the outer plate 27" does not extend above the general floor-level of the car. In this construction the door 28" is pivotally mounted in the same manner as already described at 37 and operated by a similar bracing-handle. As shown, a series of such openings and doors is arranged along the floor of the car at each side of its middle portion, and as each opening is provided with separate independently-operated doors the contents of the car may be discharged at either side or at any point as to its length within the range of the series of doors. This is of considerable advantage in unloading various materials which will run out of the hopper-openings by gravity or which may be shoveled to any particular opening.

As stated, the flooring 11 may be inclined or flat, as desired, and as thus constructed the car is capable of carrying many varieties of freight—such as coal, ore, &c., in bulk, or lumber, rails, or other longitudinal bodies—which may be loaded along and upon the various rigid cross members and upon the permanent end flooring.

For the purpose of bracing the center of the cars from the sides I employ a truss-rod 38, passing through the side sills, as shown, and secured by nuts, deflected at its middle portion downwardly and passing underneath a block 39, adapted to support the center sills. If desired, the arrangement of the truss member 38' may be reversed, as shown in Fig. 13, in which case the side sills are supported from the center sills, and it will be understood that either such forms of bracing may be adopted according to the uses for which the car is designed or as the under structure is arranged with relation to the body-bolster. Such brace members are preferably located at intervals across the car between the cross-plates and secure and rigidly brace and tie the various parts together in a strong and compact manner. As thus constructed my improved car is entirely composed of metal so incorporated as to provide simplicity and economy of construction with strength, durability, and adaptability to a wide variety of uses. The foundation structure, the sides, and ends are well connected and braced, the strains are equally disposed throughout, while the doors and their manner of operation extend the adapt-

ability of the car to a wide variety of applications and utilization.

Changes and variations may be made in the design, details, or other elements of the invention by the skilled mechanic; but all such changes are to be considered as within the scope of the following claims.

Having described my invention, what I claim is—

1. A metallic car composed of a foundation-framework of flanged structural members, corner, side and body-bolster posts of structural members secured thereto, sides and ends of plates secured to the posts, longitudinal structural members at the upper edges of the sides and supported on the posts, diagonal bracing members bearing at their inner ends against the tops of the center posts and underneath the longitudinal members and at their outer ends against the body-bolster posts, substantially as set forth. 80

2. A metallic car composed of a foundation-framework of flanged structural members, corner side and body-bolster posts of structural members secured thereto, sides and ends of plates secured to the posts, longitudinal structural members at the upper edges of the sides and supported on the posts, diagonal bracing members bearing at their ends against the tops of the center posts and underneath the longitudinal members and at their outer ends against the body-bolster posts, and longitudinal truss members passing underneath the framework and connecting the body-bolster posts, substantially as set forth. 100

3. In a car provided with side and center sills, and a middle cross supporting-bolster underneath said side and center sills, with sides mounted on the side sills, a truss member passing through the body-bolster posts, and underneath the middle supporting-bolster at each side, substantially as set forth. 105

4. In a car provided with side and center sills, and a middle cross supporting-bolster underneath said side and center sills, with sides mounted on the side sills; a truss member passing through the body-bolster posts and underneath the middle supporting-bolster at each side, and oppositely-disposed compression members arranged above such truss, bearing against the center and body-bolster posts, substantially as set forth. 110 115

5. A metallic car composed of a foundation-framework of structural members, sides and ends of plates, permanent floors at each end, and hopper-sections at each side of the middle portion of the car provided with individually-operated doors, substantially as set forth. 120 125

6. A metallic car composed of a foundation-framework of structural members comprising side sills, center sills and end sills, corner-posts and side posts connected therewith, sides and ends of plates, permanent floor members at each end, intervening plate-partitions, laterally-inclined hopper-bottom sec-

tions, and independently - movable doors adapted to open and close said hoppers, substantially as set forth.

7. In a metallic car the foundation of side, center, end and cross sills of channel members, corner - posts and inside and outside posts secured to the side and end sills, plates forming the sides and ends secured to said posts, upper lateral top members, longitudinal truss-braces in the sides, permanent floor sections at each end and intervening hopper-sections, with individually - operated doors, substantially as set forth.

8. In a metallic car the combination with side, end and center sills of channels having top and bottom flanges on common levels: top and bottom cross-bracing end sill members consisting of channels having their flanges extending upwardly and downwardly respectively, and secured to the side, center and end sills at the ends of the car, substantially as set forth.

9. In a metallic car having center and side sills, cross members consisting of plates connected with the sills, inclined hopper-bottoms extending from the plate of one partition to the other, and pivotally-mounted doors carried by supports mounted in the cross-plates, substantially as set forth.

10. In a metallic car having center and side

sills, cross members consisting of plates connected with the sills, inclined hopper-bottoms extending from the plate of one partition to the other, and pivotally-mounted doors carried by supports mounted in the cross-plates, 35 with operating - levers adapted to hold the doors in an open or closed position respectively, substantially as set forth.

11. In a metallic car provided with side and center sills of channel members, a series of 40 cross partition members, sectional hopper-bottoms secured between said plate members provided with an outside opening, a pivotally-mounted door, adapted to open and close such opening, mounted in bearings secured 45 to the cross members, with means for locking the doors in an open or closed position respectively, substantially as set forth.

12. In a metallic car provided with central and side sills of structural members: truss- 50 braces, consisting of tension members passing through the side sills and underneath the center sills, substantially as set forth.

In testimony whereof I affix my signature in presence of two witnesses.

CYRUS M. CARNAHAN.
